UNITED STATES PATENT OFFICE.

FRANK L. FAIRCHILD, OF PHILADELPHIA, PENNSYLVANIA.

DESIGN FOR A WINDOW-SASH TIGHTENER.

SPECIFICATION forming part of Design No. 32,814, dated June 12, 1900.

Application filed April 17, 1900. Serial No. 13,276. Term of patent 7 years.

To all whom it may concern:

Be it known that I, FRANK L. FAIRCHILD, a citizen of the United States, residing at No. 22 East Clapier street, in the city of Philadelphia, State of Pennsylvania, have invented and produced a new and original Design for a Window-Sash Tightener, of which the following is a specification, reference being had to the accompanying drawings, forming part thereof.

My window-sash tightener is shown in the drawings, in which—

Figure 1 is a side view, and Fig. 2 a top view, of the article.

As shown in the drawings, the leading or material features of my design consist in an approximately-circular central body portion B, containing a countersunk screw-hole.

From this body portion springs tangentially on one side the curved arm A, which tapers ²⁰ down to a thin edge by a bevel on the front side. From the body portion also springs the handle D, having gently-curved sides and a rounded end.

Having described my invention, what I ²⁵ claim, and desire to secure by Letters Patent, is—

The design for a window-sash tightener as herein shown and described.

In testimony whereof I have signed my ³⁰ name in the presence of two subscribing witnesses.

FRANK L. FAIRCHILD.

Witnesses:

JAMES F. COURTNEY,
ADA H. CLONER.
